UNITED STATES PATENT OFFICE.

JOSEPH HOPKINSON, OF DAYTON, OHIO, ASSIGNOR TO DAYTON SCALE COMPANY, OF DAYTON, OHIO, A CORPORATION OF NEW JERSEY.

WEIGHING SCALE.

Application filed March 16, 1926. Serial No. 95,008.

This invention pertains to weighing scales of the (even balance) automatic type in which the goods pan and weight pan are connected for parallel motion, and having 5 between the pans an upright housing which encloses the automatic counter-balancing and indicating devices.

Some of the scales of this type have their 10 automatic indicating charts parallel to a vertical plane drawn through the centers of the pans, while others have their charts at right angles to that plane.

The particular object of this invention is 15 to disclose a modification of such a scale in which the chart and housing enclosing it may easily be changed to face in any desired direction, either by the manufacturer or by the user. Attempts have been made to solve 20 this problem but without entire success. It has been proposed to mount the upright housing rotatably on top of the casing which 25 encloses the lever system of the scale but that is not satisfactory as it requires a heavy base casing as well as otherwise unnecessary machine work thereon, thereby adding to the 30 cost of the machine. Also, other designs have not been symmetrical in appearance, the center of the vertical housing not being on the center line of the balance of the machine.

35 My present invention discloses a design in which the vertical housing is carried not on the casing of the base lever system but on the base that supports the working parts of the scale, thereby not only providing a suitable rigid foundation for the housing, but 40 permitting the use of a very light casing for the base levers, if desired. My design is also symmetrical in outline whichever direction the chart may be facing, thereby adding to 45 the attractiveness of the appearance of the machine.

In the drawings,

Fig. 1 is a side elevation partly in section of my complete machine.

45 Fig. 2 is a plan in section on line 2—2 of Fig. 1 showing one position of vertical housing relative to goods pan.

50 Fig. 3 is a plan in section on line 2—2 of Fig. 1 showing another position of vertical housing relative to goods pan.

55 Fig. 4 is an enlarged detail view of the swivel connection on the lower end of the tape which connects the cam to the lever system.

Fig. 5 is a longitudinal sectional view on

line 5—5 of Fig. 6 showing a particular modification of a machine embodying my invention.

Fig. 6 is a sectional view on line 6—6 of Fig. 5.

In Fig. 1, 10 is the base of the machine and 60 12 is a centrally located upright pillar or pedestal rigidly mounted on base 10. 14 is the main lever of the even balance lever system, which for purpose of illustration is assumed to be of the Beranger type. Other 65 lever systems may be used if desired, as the particular form of lever system has no bearing on the invention. Lever 14 is pivotally mounted on pillar 12 at 16, and the lever 70 system carries in the well known manner a weight pan 18 and a goods pan 20. The casing 22 encloses the base mechanism, suitable 75 openings through the top of the casing being provided for the stems of the pans and for standard 12.

The upper portion of pedestal 12 is preferably in the form of a circular tube, on which is snugly fitted the lower end of upright housing 23, which may be rotated to 80 face in any desired direction, being held in position as by a set screw 24. The lower edge of housing 23 is beaded as at 26 or otherwise enlarged in any preferred manner to 85 cover easily the ring shaped space between pedestal 12 and casing 22, thereby helping to keep dust and dirt out of the base without expensive fitting of parts.

Fast to the skeleton 28 which supports weight pan 18 is an arm 30 extending upwardly into housing 23 and having at its free end a cone shaped pivot 32 located exactly on the vertical center line of pillar 12 and housing 23.

Arm 30 is connected to pendulum cam 34 95 by tape 36, provided at its lower end with a shackle 38 which carries a cup bearing 40 in which rests the cone pivot 32. Shackle 38 is so designed as to permit wide rotation in either direction before contacting with 100 arm 30. Shackle 38 must be kept out of contact with arm 30 and the above feature renders unnecessary any adjustment of the tape connections when making any ordinary adjustment of vertical housing 23.

42 is a 105 guard plate hanging freely from a pin in shackle 38 to prevent arm 30 from accidentally rising sufficiently to allow pivot 32 to rise out of its bearing 40. Plate 42 may be swung to one side whenever the operator 110

wishes to separate arm 30 and shackle 38, intentionally. An opening is provided in housing 23 at 44 to provide access to the above bearing for assembly and adjustment purposes. This opening is normally closed by a cover such as 46.

During the manufacture of the scale, after the base lever system is assembled, casing 22 is slipped over the top of pillar 12 and 10 then upright housing 23 is placed in position and fastened by screw 24. Connection of shackle 38 to arm 30 is made through opening 44.

I have illustrated the preferred form of 15 my design, but it should be understood that modification of details may be made without departing from the spirit of my invention. Such a modification is shown in Figs. 5 and 6, to the various parts of which have been 20 applied the same reference numerals used in Figs. 1, 2, 3 and 4.

In Figs. 5 and 6, upright housing 23 is joined to pedestal 12 by a flange 50, locked in position by screws 52 in place of the telescopic joint previously described. The base lever casing 22 has a removable top plate 54, and a removable collar 56 serves to enclose the space between cover plate 54 and the central vertical housing 23. The removable 25 portion 56 of the vertical housing is secured to flange 50 by a dowel pin 58.

Adjustable bumpers 60 are provided on which rest one or the other of cross members 62 of lever 14 when in its lowest position. 35 Shot cups 64 furnish convenient receptacles for balancing material. 66 is a level set into cover plate 54, and 68 is a vibration-checking dash pot having its plunger attached to a cross arm 62 by a horizontal bracket 70.

40 An opening 72 is provided in casing 22 to permit access to the dash pot for adjustment or filling. Opening 72 is normally closed by a door 74 pivoted at 76.

45 For the purpose of aiding the adjustment of the scale for accurate weighing, the fulcrum bearing stands 78 of auxiliary levers 80 are settable lengthwise of the machine by means of screws 82.

50 Arm 30 instead of being fast to the platform skeleton 28, is secured to an end of one of the levers 80, which moves the same vertical distance as the platform. The remaining details of the lever system of Figs. 5 and

6 require no further description as they are of the well known Beranger type.

55

I claim:

1. In an automatic weighing scale, in combination, a base, a lever system, a casing enclosing said lever system, a chart, an indicator cooperating therewith, and an upright 60 housing enclosing said chart and indicator, said upright housing being so supported from said base, independently of said enclosing casing, as to be rotatable about a vertical axis.

65

2. The invention set forth in claim 1, in which means is provided to lock said vertical housing for operation in any desired position.

3. In an automatic weighing scale, in combination, a supporting base, an equal arm type of lever system supported for operation on said base, an enclosing casing for said lever system, a pendulum, a chart, an indicator cooperating therewith, a housing supporting said pendulum, chart, and indicator for operation above said lever system, said housing being mounted for rotation on said base independently of said enclosing casing.

75

4. In an automatic weighing scale, in combination, a base, an equal arm lever system mounted for operation on said base, a casing enclosing said lever system, a chart, an indicator cooperating with said chart, said chart and indicator being supported for operation 80 above said lever system, a housing enclosing said chart and indicator, said housing and chart being rotatable about a vertical axis to a plurality of operative positions, said casing and vertical housings being symmetrical 85 about a common vertical axis in any operative position of the vertical housing.

90

5. In an automatic weighing scale, in combination, a base, a lever system, a casing enclosing said lever system, a chart, an indicator cooperating therewith, and an upright 95 housing enclosing said chart and indicator, said upright housing being supported on the base by a telescopic tubular joint by means of which said upright housing may be rotated about a vertical axis to any desired 100 operative position.

In testimony whereof I hereto affix my signature.

JOSEPH HOPKINSON.
